UNITED STATES PATENT OFFICE.

HENRY GUDERJAHN, OF WESTFIELD, WISCONSIN.

RAILROAD-TIE.

1,089,211.

Specification of Letters Patent.

Patented Mar. 3, 1914.

Application filed August 1, 1913. Serial No. 782,489.

To all whom it may concern:

Be it known that I, HENRY GUDERJAHN, a citizen of the United States, residing at Westfield, in the county of Marquette and State of Wisconsin, have invented new and useful Improvements in Railroad-Ties, of which the following is a specification.

The present invention relates to improvements in railroad ties, and rail fastenings therefor, and the improvement resides in the construction, combination and operative arrangement of parts set forth in the following specification and falling within the scope of the appended claim.

In the drawings: Figure 1 is a perspective view of a rail tie constructed in accordance with the present invention and showing two rails supported thereon, Fig. 2 is a transverse sectional view approximately on the line 2—2 of Fig. 1, Fig. 3 is a similar view on the line 3—3 of Fig. 1, Fig. 4 is a longitudinal sectional view on the line 4—4 of Fig. 2, Fig. 5 is a bottom plan view of the tie, Fig. 6 is a top plan view of the tie, the securing elements for the rails being removed, Fig. 7 is a perspective view of one of the rail engaging members, Fig. 8 is a horizontal section through one end of the tie illustrated in Fig. 1, Fig. 9 is a detail central vertical longitudinal section through one end of the tie, the rail engaging members shown in Fig. 8 being arranged thereon, and Fig. 10 is a perspective view of a modified form of a rail engaging member.

Referring now to the drawings in detail, the numeral 1 designates the tie which is preferably constructed of metal, and which comprises a hollow member which includes a top 2, angular sides 3 and ends 4. The ends of the tie are arranged at a right angle to the horizontally flat top or upper surface 2 of the tie, and as stated, the sides 3 are angular, that is, the sides slope downwardly and outwardly from their connection with the top to the lower portion of the said sides, and the said sides from the ends 4 of the tie have their lower edges curved, as at 5, so that the central portion of the sides is disposed a suitable distance above the opposite ends of the said sides at their juncture with the ends 4 of the tie. The underface of the hollow tie is provided with a centrally arranged longitudinally extending rib 6, and the said underface is also centrally provided with a transversely arranged rib 7 which is formed integral with

the rib 6 and extends from the opposite sides of the said rib to its connection with the inclined or angular sides 3 of the top.

The upper face or the top 3 adjacent the opposite ends thereof is formed at its side edges with transverse members 9 which are elevated above the tie and have their upper faces horizontally straight. The members 9 serve as rests for the rails, and the top of the tie, at the corners thereof, are provided with plates 8 which project above the rail rests 9 and which extend in opposite directions from the said rests. The plates 8 have their inner faces, at their juncture with the top 70 of the tie grooved longitudinally as indicated by the numeral 10. The rests 9 are of a width approximately equaling the width of the base flanges of the rails 11, and the said flanges are also adapted to have their 75 longitudinal edges contacted by the inner faces of the plates 9, when the said rails are arranged upon the tie. To provide for a tight frictional engagement between the ends of the plates 8 and rails, the said ends 80 are slightly inclined inwardly and downwardly from the upper portions of the said plates. The pairs of plates 8, adjacent their outer ends are provided with registering openings 12, while arranged for movement 85 between the said plates are rail locking members 13. Each of these locking members includes a substantially rectangular body portion 14 which is of a width approximately equaling the distance between the spaced 90 plates 8. The members 13 have their sides, at their base portions, provided with outwardly turned tongues 15 which are adapted to be received within the grooves 10 of the plates 8. One of the ends of each of the locks is 95 provided with an inclined rail-engaging lip 16, while the opposite end is undercut, and the inner wall thus provided is beveled or inclined, as at 17. The transverse inclined wall 17 of each of the locks is adapted to be 100 disposed adjacent the registering openings 12 in the plates 8, and passing through the said openings are wedge members 19 which are adapted to frictionally engage with the transverse wall 17 of the locks and to underlie the ledge 18 which forms the upper wall of the undercut end of the lock members 13. The reduced ends of each of the wedge members 19 is provided with a plurality of openings 20, and one of said openings is adapted 110 to receive the securing element, in the nature of a cotter pin 21, or if desired, other

suitable securing elements may be employed. The openings 12 are substantially rectangular and the wedge keys 19 are tapered only on one edge, so that the said key may 5 be inserted within the openings 12 from either side of the tie.

In Figs. 8 and 9 I have illustrated a slightly modified form of rail-engaging member. These members, indicated by the 10 characters A, are substantially similar to the members 14, each having their longitudinal sides shaped to engage with the longitudinally extending pairs of plates 8 and being provided with flanges which engage within 15 the grooves 10. The outer ends of the members A are notched and the transverse wall thus provided is arranged at an angle to the longitudinal plane of the said member A to coact with the wedge-members 19. The forward ends of each of the members A are 20 provided with rail engaging lip 16', while disposed below the said lip and above the flanges that enter the grooves of the plates 8 is an integrally formed longitudinally extending bearing surface or ledge B. Each 25 of the ledges B are extended a distance approximately equaling one-half of the elevated rail rest 9, so that the said ledges will rest upon the said portions 9 of the tie, and in this instance the said ledges are adapted 30 to provide a bearing surface for the flanges of the tie. This structure provides for the reception upon the tie of rails of varying heights, and also the structure provides for 35 the sustaining of broken rails upon the tie, as it is merely necessary to partially cut-

away the base flanges of the rails and allow the ledges to be received within the said cut-away portions. The lips bear directly against the base flanges and the webs of the 40 rails when in engaging position.

From the above-description, taken in connection with the accompanying drawings the simplicity of the device as well as the advantages thereof will, it is thought, be perfectly 45 apparent to those skilled in the art to which such inventions appertain without further detailed description.

Having thus described the invention, what 50 I claim is:

A metallic tie including a horizontally straight top, ends and angular sides, the top, adjacent its ends, having transverse integrally formed elevated rail rests, the said top at the edges thereof being formed with integral plates which extend longitudinally in opposite directions from the rail rests, the sides of the top having their lower edges curved upwardly toward the center of the tie, a central longitudinally extending rib 60 formed on the lower face of the top, said rib terminating away from the ends of the tie, and a transverse rib formed with the top and the sides of the tie and connected centrally to the longitudinal rib. 65

In testimony whereof I affix my signature in presence of two witnesses.

HENRY GUDERJAHN.
